UNITED STATES PATENT OFFICE.

CHARLES CORLISS McBRIDE, OF SANGER, CALIFORNIA.

DEVICE FOR RECOVERING PRECIOUS METALS.

Application filed July 3, 1923. Serial No. 649,262.

To all whom it may concern:

Be it known that I, CHARLES CORLISS McBRIDE, a citizen of the United States, and resident of Sanger, in the county of Fresno and the State of California, have invented a new and useful Improvement in Devices for Recovering Precious Metals, of which the following is a specification.

My invention relates to a device for recovering gold, platinum and other metals from sand, crushed ore, tailings and fine material containing those metals.

The object I have accomplished is the recovery from sand, crushed ore, tailings and waste material, precious metals such as gold and platinum, whether said metals are in the form commonly known as flakes or finely divided metal, or in larger particles. A more specific object is the application of an amalgamated plate kept moist with a chloride solution which is energized by a current of electricity for separating the precious metals from a precious metal bearing material saturated with fresh water.

This object is accomplished by means of the device hereinafter described and illustrated on the accompanying drawing in which Figure 1 is a side perspective view with parts cut away to show the inside portions of the device. Figure 2 is a lateral sectional view of the device. Figure 3 and 4 are modified forms of the cylinder construction.

In said drawing I have shown a drum or cylinder 4, constructed preferably conical, having an axis or shaft 5 attached thereto and projecting from the ends, for the purpose of revolving it. The rotation may be accomplished otherwise than on an axis by any of the well known means for revolving a cylinder. The cylinder shown in the drawing consists of a spiral ribbon 6, a screen 7 surrounding the ribbon and attached thereto, and a covering 8 on the outside of the screen. In my experiments I used a canvas covering, but other material may be used. In the drawing I have shown the screw or spiral ribbon constructed so that the cylinder should be rotated opposite to the hands of a clock but it can be constructed to run the other direction. The smaller end of the cylinder is slightly elevated above the level of the larger end. Openings are provided surrounding the axis at each end of the cylinder, the openings 9 at the larger end being

the intake opening, and an outlet opening 10 being at the smaller end. A trough 11 is placed directly under the outlet opening 10 to carry away the refuse. A tank 12 contains an electrolyte solution, preferably an alkali chloride solution, and the cylinder is arranged in relation to the tank so that the under part of the cylinder is submerged in the chloride solution as it revolves. In Figure 2, line 16 shows the approximate level of the electrolyte.

Describing certain of the parts more in detail, it is noted that the spiral ribbon decreases in width as it extends from the intake opening toward the outlet opening, so that the riffles formed thereby on the lower part of the cylinder when in operation, as shown in Figure 2, decreases in height regularly from intake to discharge opening. It is also noted that the angle of the dip of the cylinder is such that the top of the riffle at the outlet end of the cylinder is on a level with a point about the riffle at the intake end of the cylinder and slightly above the bottom of the intake opening, the line of this level being shown as 13. The object of this construction is to permit the water and light material carried thereby to return over the top of the riffles formed by the spiral ribbon toward the intake opening. This same object can be accomplished by narrowing the space between the coils of the spiral ribbon as it approaches the outlet, thus raising the matter carried forward in the spiral. The discharge opening 10 is on a level with the top of the riffle at the discharge end of the cylinder. I have introduced a current of electricity into the electrolyte and through the cylinder, the lead 14 being positive and lead 15 being negative.

There is also shown on the drawing a hopper 17 for carrying the metal bearing material into the cylinder, bearings 18 and 19 for carrying axis 5, and a spout 20 at the intake opening which also serves as a second discharge opening under conditions and for the purposes hereinafter explained. The canvas covering permits water to permeate it, but is close enough woven so that the solution in the tank does not freely commingle with the water in the cylinder.

It has heretofore been disclosed in applications filed by me for patents, September 28, 1921, Serial No. 503,897, amalgamating sluice, and United States patents allowed

as follows: No. 1,447,140, February 23, 1923, process for extracting precious metals, and No. 1,430,091, amalgamating cell, dated September 26, 1922, that when gold or platinum bearing sands or material pass over an amalgamated plate while a current of electricity is led from an anode submerged in a chloride solution to the amalgamated plate, which functions as a cathode, the precious metals will adhere to the amalgamated plate. This principle is applied in my present invention by the metal screen performing the function of the amalgamated plate, being formed into a cathode by the negative current conveyed by line 15 to the plate, and the amalgamated screen is further energized by passing a current of electricity through the covering of canvas which is kept saturated with the electrolyte. In operating this device the metal bearing material is mixed with water, which may be fresh, until it forms a pulp, when it is put into the cylinder through the intake opening. As the cylinder revolves the pulp is moved toward the discharge opening by means of the spiral ribbons, and the movement keeps the pulp in a constant agitation, thus bringing much of it in direct contact with the amalgamated screen, and the precious metals will adhere to the screen. It is noted that during the travel of the pulp through the cylinder as noted the heavier particles naturally go toward the bottom and the lighter particles remain on the top, and in this connection the tilting of the cylinder as described and the diminishing width of the ribbon from intake to discharge functions by starting a current of the fluid and light particles carried thereon from the discharge opening toward the intake opening, where the light material and fluid are discharged through the second discharge opening, being the lower portion of the intake opening 9, through spout 20. By this means the finely divided metals or flake metals are not floated away but can be recovered and worked over. It is here noted that an amalgamated plate without the energizing effect of a chloride solution and an electric current will function to a lesser degree in collecting particles of gold and platinum, and my device can be used with a lesser degree of efficiency without the chloride solution and the electric current, and the canvas cover can be substituted by a metallic one, and the amalgamated screen can be substituted by an amalgamated plate.

The arrow 21 shows the direction of the rotation of the cylinder shown in Figure 1. In Figures 3 and 4 I have shown modified forms of cylinders. In Figure 3, 37 is a coil of amalgamated wire surrounding a spiral ribbon, the coil being a substitute for the screen, and in Figure 4 I have shown strips 38 of amalgamated metal wrapped as a coil.

In each of these forms the wire or strips are spaced apart. The shell 27 is adapted to hold the canvas against the cylinder.

Having described my invention, I claim as new and ask for Letters Patent: 70

1. In a device for the recovery of precious metals, the combination of a rotatable porous cylinder lined with an amalgamated screen, said cylinder having intake and discharge openings at opposite ends, a spiral ribbon 75 within the cylinder and adapted with the rotary movement of the cylinder to carry loose particles therein from the intake to the discharge opening, the cylinder being positioned so the axis is lower 80 at the intake opening end, and means for submerging portions of the cylinder in an electrolyte solution.

2. In a device for the recovery of precious metals the combination of a rotatable cylinder lined with an amalgamated screen, said cylinder having intake and discharge openings at opposite ends, a spiral ribbon within the cylinder and adapted with the rotary movement of the cylinder to carry 85 loose particles therein from the intake to the discharge opening, the said ribbon decreasing in width from the intake opening toward the discharge opening, the cylinder being positioned with the axis sufficiently 90 lower at intake end of the cylinder so that a line across the top of the ribbon parallel with the axis and directly under it would tilt toward the intake opening, substantially 95 as described. 100

3. In a device for the recovery of precious metals the combination of a rotatable cylinder constructed of an amalgamated screen and having a canvas outside covering, inlet and discharge openings at opposite ends 105 of the cylinder, and a spiral ribbon within adjacent to the inside periphery of the amalgamated screen, the spiral ribbon being adapted in combination with the rotary movement of the cylinder to move loose 110 particles therein toward the discharge opening of the cylinder, and means for keeping the canvas covering saturated with an electrolyte fluid, substantially as described. 110

4. In a device for the recovery of precious metals the combination of a rotatable cylinder constructed of an amalgamated screen and having a canvas outside covering, inlet and discharge openings at opposite ends 115 of the cylinder, and a spiral ribbon within adjacent to the inside periphery of the amalgamated screen, the spiral ribbon being adapted in combination with the rotary movement of the cylinder to move loose 120 particles therein towards the discharge opening of the cylinder, and means for keeping the canvas covering saturated with a chloride solution and for passing an electrical current through the solution and the amalgamated screen. 125 130

5. In a device for the recovery of precious metals the combination of a rotatable cylinder constructed of an amalgamated screen and having a canvas outside covering, inlet and discharge openings at opposite ends of the cylinder, and a spiral ribbon within adjacent to the inside periphery of the amalgamated screen, the spiral ribbon being adapted in combination with the rotary movement of the cylinder to move loose particles therein toward the discharge opening of the cylinder, and means for keeping portions of the canvas immersed in a chloride solution, substantially as described.

15 6. In a device for the recovery of precious metals, the combination of a rotatable cylinder constructed of an amalgamated screen and having a canvas outside covering, inlet and discharge openings at opposite ends of the cylinder, and a spiral ribbon within adjacent to the inside periphery of the amalgamated screen, the spiral ribbon being adapted in combination with the rotary movement of the cylinder to move loose particles therein toward the discharge opening of the cylinder, and means for keeping portions of the canvas immersed in a chloride solution, and means for passing an electrical current through the solution and the amalgamated screen.

35 7. In a device for the recovery of precious metals the combination of a rotatable cylinder with an amalgamated interior surface, an inlet and an outlet opening at opposite ends, a spiral ribbon within the cylinder adjacent to the inside periphery, and adapted to move a continuous current of pulp and electrolyte fluid towards the discharge end as the cylinder is rotated, and means for passing an electrical current through the electrolyte and pulp.

40 8. In a device of the character described, the combination of a rotatable cylinder of amalgamated wire mesh, closed ends in the cylinder except for outlet and discharge openings in opposite ends thereof, a spiral ribbon within the cylinder adjacent to the periphery adapted to move loose material within the cylinder toward the discharge opening when the cylinder is being rotated, and means for keeping the under portion of the cylinder submerged in a chloride solution.

45 9. In a device for recovering metal, the combination of a rotatable cylinder of amalgamated wire mesh, closures at each end, except for an intake opening at one end, and a discharge opening at the other end, a spiral ribbon within the cylinder adapted to move loose material toward the discharge

opening as the cylinder revolves and a covering for the cylinder composed of absorbative material.

50 10. A device for recovering metals consisting of a rotatable cylinder the shape of the frustum of a cone, said cylinder being amalgamated wire mesh, closures at each end of the cylinder except an inlet opening at large end and a discharge opening at the small end, a spiral ribbon within the cylinder adapted with the rotary movement of the cylinder to move loose material therein toward the discharge opening, a covering for the outside of the cylinder of absorbative material and means for keeping said outside covering saturated with a chloride solution.

55 11. A device for recovering metals consisting of a rotatable cylinder the shape of the frustum of a cone, said cylinder being amalgamated wire mesh, closures at each end of the cylinder except an inlet opening at large end and a discharge opening at the small end, a spiral ribbon within the cylinder adapted with the rotary movement of the cylinder to move loose material therein toward the discharge opening, a covering for the outside of the cylinder of absorbative material, and means for keeping said outside covering saturated with a chloride solution, and means for passing an electrical current through the saturated covering and the amalgam cylinder.

60 12. In a device for recovering precious metals, the combination of a spiral ribbon covered on outside periphery with amalgamated wire placed thereon to form a cylinder, the wire being spaced to form openings into the cylinder, closures at the ends of the cylinder except for an inlet and an outlet opening at opposite ends thereof, a covering on the outside of said cylinder constructed of substance susceptible of capillary attraction, means for applying a bath of chloride solution to the covering, and means for rotating the cylinder.

65 13. In a device for recovering precious metals, the combination of a rotatable cylinder constructed of amalgamated metal having interstices therethrough, closures at each end except for an inlet opening at one end, a discharge opening at the other end, a spiral ribbon within the cylinder adapted to move loose material within the cylinder toward the discharge end of the cylinder when the cylinder rotates, an absorbent covering for the cylinder and means for keeping the covering saturated with an electrolyte.

CHARLES CORLISS McBRIDE.
